UNITED STATES PATENT OFFICE

2,034,482

FLASHLIGHT APPARATUS

Phelps Olds, Little Neck, N. Y.

Application March 31, 1934, Serial No. 718,318

11 Claims. (Cl. 67—29)

The invention relates to flashlight apparatus, and more particularly to a mechanism ensuring accuracy in the timing of the actuation of the camera shutter, and of the energizing of the flash bulb.

I have heretofore produced an apparatus of this type embodying two pivotally connected members carrying co-operating electrical contacts controlling the circuit to the flash bulb, one of 5 these members being adapted to be connected with the sheathing of a shutter actuating cable, and the other of which is adapted to engage the movable wire of the cable.

With this construction, it was not only possible 10 by the arrangement of the contacts and of the arrangement of the cable in relation thereto, to secure, by a quick action of the hand, a differential movement between the contacts and the cable slide, in a manner to secure the desired timing in 15 the shutter movement and in the ignition of the tinsel in the bulb, but also a desired rapidity in the actuation of the control mechanism to permit the operator to catch a particular pose of the 20 subject. The said device, in the hands of a skilled photographer, produces satisfactory results, but the adjustment and the manipulation of the device required, to get the best results, the acquired 25 skill of an expert photographer.

With the above conditions in mind, I have produced improvements in the structure of the flashlight apparatus above referred to, which will 30 adapt it for use by amateurs, and permit the adjustment of parts with an accuracy permitting 35 the device to be used with high speed shutters and still maintain a desired timed relation between the actuation of the shutter and the illumination of the bulb.

With the structure of my present invention, 40 the pivotal members, irrespective of the setting of the device, always have the same quantity of movement, thus controlling the operation of the device by adjustments therein instead of requiring the skill of the operator to compensate for 45 those conditions influencing the operative effect of the control, such as varying temperature conditions which have a tendency to delay the ignition of the tinsel in the bulb following the closing of the circuit by the control device.

In the device of the invention, the relative 50 movement of the two pivotal members in their action upon the contacts controlling the circuit is always the same, any variation in the timing 55 of the shutter action and the ignition of the bulb

being controlled by the operative effect of these members upon the shutter cable.

The device is so made as to not only adapt it to use with cables of different structure, but means are provided whereby the sheathing of the cable, irrespective of the size of its nipple fitting, may be held against any displacement which may tend to vary the operative effect of the control upon the shutter.

In conjunction with the control mechanism 10 above referred to, I provide a bulb support which may be detachably connected with the camera box by means of the screw sockets provided for the purpose of securing the camera to a tripod, thus permitting the bulb carrier to be mounted 15 upon the camera or to be held or located more or less remote from the camera, if desired.

In snapshot work, it is frequently necessary 20 for a photographer to take pictures in rapid succession. It is necessary after every actuation of 25 the flashlight, to remove the bulb and replace it with a fresh bulb. I therefore so construct the bulb carrier as to permit the rapid mounting of 30 bulbs therein and their removal therefrom.

The invention consists primarily in a flashlight 25 apparatus embodying therein the combination with a camera having a shutter and a mechanical release mechanism therefor having immovable and movable elements, of a support for a flash 30 bulb, a control device embodying therein two members pivotally connected adjacent one end thereof, means adjacent the free end of one of 35 said members, whereby one of the elements of said release mechanism may be connected therewith, an adjustable member carried by the other of said members adapted to engage the other element of said release mechanism, and co-operating fixed and movable electrical contacts intermediate said means and said adjustable member, 40 and the axis of movement of said pivotal members, whereby the timing of the engagement of said contacts and the actuation of said release mechanism, may be varied without variation of the 45 relative movement of said members, and an electrical circuit including said bulb and said contacts; and in such other novel features of construction and combination of parts as are herein-after set forth and described, and more particularly pointed out in the claims hereto appended.

Referring to the drawing,

Fig. 1 is a view of a camera having attached thereto a flashlight apparatus embodying the invention;

Fig. 2 is a longitudinal view in section of the control mechanism;

Fig. 3 is a front elevation of said control mechanism;

5 Fig. 4 is a detailed view of the means for attaching one of the cable elements to the control device;

Fig. 5 is a view, partly in elevation, of the bulb support upon a larger scale; and

10 Fig. 6 is a sectional view of the mechanism used in attaching the bulb support to the camera box.

Like numerals refer to like parts throughout the several views.

Flashlight bulbs of the type with which the 15 apparatus of the invention is designed to be used, may vary as to the lighting effects secured thereby, but all have in common the characteristics of a delay of approximately 1/100th of a second following the closing of the circuit thereto before the 20 ignition of the bulb. This is followed by a rapid attainment of the maximum illuminating effect, a rapid decrease in this effect and a gradual fading out of the light. The period of approximate maximum illumination is about .0025 of a second, 25 a lessened brilliant illuminating effect, however, continuing after the maximum has been reached for approximately .01 of a second after which the lighting effect is negligible.

In taking snapshots, if the camera is to be held 30 by hand, the shutter speed must be at most 1/25th of a second, and with the ordinary camera with flashlight work, the speed of the shutter should be about 1/50th of a second. Shutter mechanisms are used, however, which attain a speed of 35 1/100th of a second.

The foregoing is mentioned in order to enable a better understanding of the invention.

In the embodiment of the invention shown in 40 the drawing, an ordinary camera is shown at 10, the camera box at 11 and the shutter mechanism at 12. Secured to the shutter mechanism is an ordinary actuating cable consisting of a sheathing 13 and a push wire 14 slidably mounted therein, the normal relative position of these parts being 45 established by means of a spring 15. The sheathing 13 is provided with a flanged end nipple 16 and the wire 14 is provided with an enlarged head or push button 17. In the cable most generally used, the sheathing 13 is fixed and the wire 14 is 50 movable in relation thereto. In adapting the mechanical actuating means of this type to cameras not equipped to have the sheathing 13 attached thereto, it is a common practice to clamp the wire 14 to the lens head and provide the 55 sheathing with a loop engaging the release lever of the shutter mechanism. With this construction, the wire 14 is fixed and the sheathing is movable. In most cameras, particularly those for use by amateurs, the box 11 is provided upon 60 opposite sides thereof and upon the support 18 for the lens head, with screw threaded sockets 19 by means of which the camera may be mounted upon a tripod.

The particular construction of the shutter 65 mechanism is immaterial to the present invention so that a detailed description thereof is unnecessary, the parts described above being referred to merely because of the utilization of these parts in adapting the control device of the invention to the camera. All the parts heretofore described, are old and well known, the control mechanism of the invention being so constructed 70 as to be adapted to many variations of such old parts.

75 The control mechanism of the invention com-

prises two members 20 and 21 pivotally connected adjacent one end thereof by means of the pivot pin 22. The rear end of the member 20 and its opposite sides are closed and carry a guide shaft 23 in the side walls and the front wall is also 5 closed except for a vertically extended slot 24 provided toward the bottom thereof with lateral enlargements 25 to facilitate the mounting of the flanged nipple of the sheathing 13 within a fitting 26 carried by the front of said lower member below said enlargements 25. The upper face of the fitting 26 has a depressed circular portion 27 toward the back thereof, and opening forwardly of this fitting is a channel 28, the rear walls of which converge at 29 meeting rearwardly 15 of the axis of the circular depression 27. This construction of fitting is employed in order to adapt the control device to cables having nipples of different sizes, the converging walls 29 serving to approximately center the nipple with relation to the actuating means for the cable carried by the upper pivotal member 21. The forked fitting 26 is provided with a screw threaded opening 30 through one of the arms thereof adapted to receive a set screw 31, the opening 30 extending substantially radially of the axis of the depression 27. In this manner, it is possible to firmly secure the nipple of the sheathing to the member 20 of the control device, thus avoiding any loss of accuracy in the actuation of the 30 cable due to movement of this nipple.

In order to increase the facility with which the nipple may be mounted in relation to the fitting 26, I provide a spring clamp plate 32 positioned above said fitting and provided with a slot 33 35 through which the wire 14 may pass, the forward end of this plate being upwardly flared as shown in Fig. 4.

Carried by the lower member 20 are a plurality of electrical contacts 34 and 35 adapted to 40 co-operate with a plug 36. These contacts are mounted in the bottom of the lower pivotal member 20 by means of an insulating bushing 37 as shown in Fig. 2 of the drawing. Also mounted upon, but insulated from the bottom of the member 20, is a spring bridge electrical contact member 38 carrying a contact block 39 of insulating material, said movable contact member 38 being engageable with the fixed contacts 34 and 35.

To prevent the end of the cable adjacent the 50 control device from engaging the switch mechanism described, I preferably provide a barrier 40 between the fitting 26 and said switch mechanism.

The upper member 21 is provided with guide 55 slots 41 receiving the guide shaft 23. This member is provided with depending flanges except at the rear thereof and has a free sliding fit within the lower member 20. Also carried by the member 21 is a striker member 42 so positioned as to 60 engage the block 39 with relative movement of the members 20 and 21. Toward the front of the member 21 is an adjusting screw 43 provided with a dished head 44 adapted to engage the push button of the wire 14 of the cable. This 65 adjusting screw 43 may be adjusted to vary the position of the operative end of said wire in relation to the shutter release mechanism, thus accurately timing the operative moment of said wire in relation to said release mechanism. A 70 lock nut 45 is used to maintain the screw 43 in any adjusted position while facilitating a quick and accurate actuation of the screw.

Secured to the member 20 in any desired manner, is a spring 46 acting upon the member 20 75

to normally raise said member to the uppermost position permitted by the slots 28.

For use by amateurs and by professionals in outdoor work, the electrical source usually employed is a dry cell battery. The flash tubes are so formed as to ignite when a current of approximately 1½ volts is applied thereto. I have found, however, that the use of a higher voltage is desirable.

10 To meet the above conditions of use, I provide a bulb support 47 having a bulb socket 48 open at both ends and having an inwardly directed bottom flange 49. Seated upon said flange is a movable plate 50 of insulating material having centrally thereof, a contact member 51. The closure 52 for the lower end of the support has mounted thereon, but insulated therefrom, a spring 53, the insulating plate for said spring being shown at 54. The flash bulb itself is shown 15 at 55 and is of the usual commercial construction having a screw threaded base. The floating plate 50 is used to permit the rapid mounting or removal of the bulb from the support.

With the construction described, the screw threads of the socket and the base of the bulb are used merely for locking the bulb in relation to the support by a partial rotation of the bulb, the socket being of a length to permit engagement of the contact member 51 with one terminal of the battery 56 before the screw threads upon the base of the bulb are in a position to mesh with the screw threads of the socket. As in ordinary flashlight apparatus not usable for photographic purposes, the spring 53 assures the desired continuous contact of the opposite poles of the battery with the contact 51 and the spring. One terminal wire 57 leading to the plug 36 is electrically connected with the spring 53 and the other terminal wire 58 leading to said plug, is 20 electrically connected with the socket 48, which is insulated from the support 47. At the top of the support 47 is a screw threaded ring 59 adapted to receive the base of a reflector to enable the bulb support to be used by holding it 25 in the hand instead of mounting it upon the camera box.

For indoor work by amateurs, it is desirable to mount the bulb support upon the camera box by means of either of the screw threaded sockets 30 19 used in mounting the camera upon a tripod; for which purpose I provide said support with a fitting 60 having an opening extending therethrough for the reception of an attaching screw 61.

5 In some cameras, the finder is located at the right of the lens head, and on other cameras, it is located at the left of the lens head. In order to adapt the bulb support to practically all makes of cameras adapted to be used upon tripods, the 10 attaching screw 61 must be reversible in the opening of the fitting 60 and to permit this, the screw 61 has a free sliding fit in said opening and is provided centrally thereof, with an elongated channel 62 adapted to be engaged by a latch pin 63 forced into the channel by a spring 64. With this construction, the screw 61 may be readily pulled from one end of the opening and reinserted therein through the opposite end. The fitting 60 is clamped against the support 47 15 by the engagement of the knurled head of the screw 61 with said fitting so as to prevent accidental tilting of the support while the camera is in use.

The operation of the herein described flashlight apparatus is substantially as follows:—

In the use of flexible cables for tripping the shutter mechanism of a camera, the movable member of the cable may have to receive from one-eighth of an inch to an inch and a quarter of movement in effecting the shutter release, the 5 quantity of this movement varying with different shutter mechanisms.

As heretofore set forth, there is an interval of approximately .01 of a second between the closing of the circuit to the flash bulb and the 10 initial ignition of the tinsel of the bulb, the maximum illumination of the bulb continues for one-quarter of .01 of a second, and the effective illumination following the maximum illumination continues for approximately .01 of a second. 15 With a shutter speed of 1/25th of a second, the exposure is sufficiently long to include substantially the full duration of the illumination from the bulb and the interval of approximately .01 of a second between the closing of the circuit 20 and the initial ignition of the bulb.

With a shutter speed of 1/50th of a second, the duration of the exposure before the bulb attains its maximum illumination is such as to make available only a small percentage of the 25 light emanating from the bulb, since the shutter closes substantially simultaneously with the initial attainment of the maximum lighting effects of the bulb. With the shutter operating at this speed, the lag of .01 of a second, above referred 30 to, is a material factor, since it cuts down the efficiency of the bulb by practically 75%.

It is obvious that with a shutter speed of 1/100th of a second, the shutter will be closed before there is any illumination from the bulb. 35 The above conditions are those prevailing with the simultaneous closing of the circuit to the bulb and tripping of the shutter mechanism.

In the apparatus of the invention, it is possible to so control the timing of the release of 40 the shutter and the closing of the circuit to the bulb by a positive constant relative movement of the members 20 and 21 as to compensate for the dark interval of .01 of a second following the closing of the circuit to the bulb irrespective of 45 the shutter speed, since even with a shutter speed of 1/25th of a second, a delay of .01 of a second between the closing of the circuit to the bulb and the release of the shutter will result in the utilization of some of the light emanating from 50 the bulb during substantially the entire exposure interval, although there will be a gradual diminution of the volume of light toward the end of the exposure.

At shutter speeds of 1/50th or 1/100th of a second, it is essential that the release of the shutter movement be timed in relation, not to the closing of the circuit to the bulb, but to the initial ignition of the tinsel in the bulb, or with the higher speed, for a slight interval after this initial ignition. 55

The time intervals involved are so short that the skill of the amateur cannot be relied upon to control any variation in the timing of the closing of the circuit to the bulb and the tripping 60 of the shutter mechanism.

A professional operator has a sense of timing which ordinarily enables him to control the movement of parts to secure such a variation, but when a picture is taken hurriedly, even a professional photographer may be unable to properly control the actuation of the shutter mechanism 70 in its relation to the ignition of the bulb.

The above refers only to the taking of snapshots, since with a "bulb" setting of the shutter 75

mechanism, the flashlight interval controls the duration of the exposure.

In the apparatus of the invention, the timing of the closing of the circuit to the bulb and of the tripping of the shutter release is controlled by a predetermined adjustment of the control device, it being merely required that the photographer press the members 20 and 21 together to the full extent and as rapidly as possible. Any variation in the speed of said members, insofar as its effect in the timing of the shutter movement and the ignition of the bulb is concerned, is negligible, even with a high speed setting of the shutter mechanism. This is due to the effective leverage at which the members 20 and 21 act upon the parts 13 and 14 of the cable and the shortness of the last part of the movement of the pusher wire 14 required to trip the shutter mechanism following the closing of the circuit at the contacts 34, 35, and 38. While the full movement ordinarily required of the wire 14 may have to be as much as one and one-quarter inches, the operative movement, with the ordinary setting of the control device, will require only approximately .01 of a second following the engagement of the contacts, which represents a very small fraction of the full movement of the wire.

If the full movement of the wire ordinarily required be as little as one-eighth of an inch, the ordinary setting of the control device must nevertheless be such as to require only approximately .01 of a second following the engagement of the contacts.

35 The final part of the movement of the wire trips the shutter, and consequently setting of the adjustment screw 43 is in relation to this final movement.

The various parts of the control device are so proportioned as to adapt it to the shortest movement required of the wire 14, and with cables for use with shutter mechanisms requiring a longer movement of the wire, the screw 43 is so set as to advance the end of the wire operation upon the shutter release to an extent to make the operative movement of the wire the same as that of a wire so constructed as to require normally a shorter movement.

Whatever the setting of the adjustment screw, 50 the relative movement of the members 20 and 21 is always the same, the timing of the ignition of the bulb and of the shutter movement being controlled by the setting of the screw 43. The contacts 34, 35, and 38 are always engaged at the 55 same point of the movement of said members, and the tripping of the shutter mechanism occurs at a point of the movement of said members, determined by the setting of the screw 43 and may be varied by adjustment of the screw to- 60 wards or from the fitting 26.

When the shutter mechanism is set for a speed of 1/25th of a second, no great nicety in the adjustment of the screw 43 is required. This is a shutter speed well suited for "snap shot" work 65 by amateurs since, good pictures may be taken while the camera is held by hand. It is required that the screw 43 be so set as to ensure a lag of approximately .01 of a second between the closing of the circuit to the bulb and the release 70 of the shutter, a variance of 25% being permissible. If the shutter speed be 1/50th of a second, considerable nicety of adjustment of said screw is necessary, since a full .01 of a second lag must be provided for, although this lag may be increased by 25% advantageously. With a shut-

ter speed of 1/100th of a second, great nicety of adjustment of the screw is necessary, since the lag should exceed .01 of a second by 50% or more.

Increase in the lag of the shutter over the 5 closing of the circuit to the bulb 55 is secured by moving the screw 43 away from the fitting 26, and the converse by moving the screw towards said fitting.

In assembling the cable in relation to the control device, the flange of the nipple 16 is passed through the channel 28 of the fitting 26, the enlargements 25 and slot 24, the wire 14 passing through said slot. The slot 28 guides the nipple into and centers it in relation to the depressed 15 portion 27, and positions the button 17 below the head 44. The nipple passes below the clamp 32, and the wire 14 passes along the slot in said plate, thus holding the nipple upon the seat 27. The set screw 31 is then engaged with the nipple 20 16 so as to firmly hold the sheathing 13 in relation to the member 20.

The screw 43 is then adjusted to secure the desired timing effects above referred to, and the lock nut 45 set to maintain this adjustment. 25

The members 20 and 21 are normally separated or biased apart, by the spring 46.

When taking a snap shot, the operator merely forces the members 20 and 21 together against the tension of the spring 46. During this movement the striker member 42 engages the plate 39 and forces the movable contact 38 into engagement with the fixed contacts 34 and 35, thus closing the circuit from the source to the bulb 55. Following this, and by a rapid continuing 35 movement of the members 20 and 21, the shutter mechanism 12 is tripped, the interval between the closing of the circuit and the tripping of the shutter mechanism being determined by the setting of the screw 43. 40

The speed at which the members 20 and 21 are moved is immaterial. Their movement is by a mere closing of the hand, and will always be rapid and full. Any variation will be negligible in its effect upon the timing resulting from such 45 movement.

When no bulb is in the socket 48, the spring 53, through the dry cells, forces the movable plate 50 upwardly of the socket until it engages the lower screw thread thereof. To mount a bulb 55 in the holder, it is merely necessary to insert its base in the socket with the contact button engaging the contact 51 and force the plate 50 inwardly of the socket against the tension of the spring 53 until the lowermost thread of the bulb base may be engaged with the uppermost thread of the socket, so that by a short turning of the bulb, said screw threads may be engaged sufficiently to hold the tension of said spring. In this manner, a bulb may be mounted in the holder by merely thrusting it into the socket and then giving it a quick short turn, and may be as rapidly removed by reversing these actions. This greatly facilitates a rapid replacement of bulbs 60 in the holder, which at times is very important. 65

The manner of mounting the holder on a camera requires no further description.

I have described the operation of the members 20 and 21 and their appurtenances in connection with a cable in which the wire 14 acts upon the shutter mechanism trip. If the sheathing 13 acts upon said trip, the result would be the same. In the former case, the shutter release is effected by movement of the top member 21, and in the 75

latter case by movement of the bottom member 20.

While ordinarily, and particularly in outdoor photography, a dry battery is used as the only available source, it is obvious that an ordinary house lighting current may be used if proper plugs are provided.

It is not my intention to limit the invention to the precise details of construction shown in the drawing, it being apparent that such may be varied without departing from the spirit and scope of the invention.

Having described the invention, what I claim as new and desire to have protected by Letters 15 Patent, is:—

1. A flashlight apparatus embodying therein the combination with a camera having a shutter and a mechanical release mechanism therefor having immovable and movable elements, of a support for a flash bulb, a control device embodying therein two members pivotally connected adjacent one end thereof, means adjacent the free end of one of said members, whereby one of the elements of said release mechanism may be connected therewith, an adjustable member carried by the other of said members adapted to engage the other element of said release mechanism, and co-operating fixed and movable electrical contacts intermediate said means and said adjustable member, and the axis of movement of said pivotal members, whereby the timing of the engagement of said contacts and the actuation of said release mechanism, may be varied without variation of the relative movement of said members, and an electrical circuit including said bulb and said contacts.

2. A flashlight apparatus embodying therein the combination with a camera having a shutter and a mechanical release mechanism therefor having immovable and movable elements, one of said elements having at one end thereof a flanged nipple, of a support for a flash bulb, a control device embodying therein two members pivotally connected adjacent one end thereof, a fitting carried adjacent the free end of one of said pivotal members, said fitting having a circular depressed portion toward the rear thereof, and a channel leading forwardly therefrom, the rear walls of said channel converging rearwardly of the axis of said depressed portion, means carried by said fitting and adapted to hold said nipple engaged with the converging walls of said channel, whereby said nipple may be firmly connected with said pivotal member, an adjustable member carried by the other of said members adapted to engage the other element of said release mechanism, and co-operating fixed and movable electrical contacts intermediate said means and said adjustable member, and the axis of movement of said pivotal members, whereby the timing of the engagement of said contacts and the actuation of said release mechanism, may be varied without variation of the relative movement of said members, and an electrical circuit including said bulb and said contacts.

3. A flashlight apparatus embodying therein the combination with a camera having a shutter and a mechanical release mechanism therefor having immovable and movable elements, one of said elements having at one end thereof a flanged nipple, of a support for a flash bulb, a control device embodying therein two members pivotally connected adjacent one end thereof, a fitting carried adjacent the free end of one of said pivotal members, said fitting having a circular

depressed portion toward the rear thereof, and a channel leading forwardly therefrom, the rear walls of said channel converging rearwardly of the axis of said depressed portion, a set screw mounted in said fitting and extending radially of said depressed portion adapted to hold said nipple engaged with the converging walls of said channel, whereby said nipple may be firmly connected with said pivotal member, an adjustable member carried by the other of said members 10 adapted to engage the other element of said release mechanism, and co-operating fixed and movable electrical contacts intermediate said means and said adjustable member, and the axis of movement of said pivotal members, whereby 15 the timing of the engagement of said contacts and the actuation of said release mechanism, may be varied without variation of the relative movement of said members, and an electrical circuit including said bulb and said contacts. 20

4. A flashlight apparatus embodying therein the combination with a camera having a shutter and a mechanical release mechanism therefor having immovable and movable elements, one of said elements having at one end thereof a flanged 25 nipple, of a support for a flash bulb, a control device embodying therein two members pivotally connected adjacent one end thereof, a fitting carried adjacent the free end of one of said pivotal members, said fitting having a circular 30 depressed portion toward the rear thereof, and a channel leading forwardly therefrom, the rear walls of said channel converging rearwardly of the axis of said depressed portion, a set screw mounted in said fitting and extending radially of 35 said depressed portion adapted to hold said nipple engaged with the converging walls of said channel, whereby said nipple may be firmly connected with said pivotal member, a spring plate above and projecting over said fitting, said spring plate 40 having a slot therein through which the other element of said release mechanism is adapted to pass, an adjustable member carried by the other of said members adapted to engage the other element of said release mechanism, and co-operating 45 fixed and movable electrical contacts intermediate said means and said adjustable member, and the axis of movement of said pivotal members, whereby the timing of the engagement of 50 said contacts and the actuation of said release mechanism, may be varied without variation of the relative movement of said members, and an electrical circuit including said bulb and said contacts.

5. A flashlight apparatus embodying therein 55 the combination with a camera having a shutter and a mechanical release mechanism therefor having immovable and movable elements, of a support for a flash bulb, a control device embodying therein two members pivotally connected 60 adjacent one end thereof, means adjacent the free end of one of said members, whereby one of the elements of said release mechanism may be connected therewith, an adjustable member carried by the other of said members adapted to engage the other element of said release mechanism, spaced fixed contacts, and a movable spring contact carried by one of said members intermediate said means and said adjustable member, and the axis of movement of said pivotal member, and a striker member carried by the other of said members and engageable with said spring contact, whereby the timing of the engagement of 70 said contacts and the actuation of said release mechanism, may be varied without variation of 75

the relative movement of said members, and an electrical circuit including said bulb and said contacts.

6. A flashlight apparatus embodying therein the combination with a camera having a shutter and a mechanical release mechanism therefor having immovable and movable elements, one of said elements having at one end thereof a flanged nipple, of a support for a flash bulb, a control device embodying therein two members pivotally connected adjacent one end thereof, a fitting carried adjacent the free end of one of said pivotal members, said fitting having a circular depressed portion toward the rear thereof, and a channel leading forwardly therefrom, the rear walls of said channel converging rearwardly of the axis of said depressed portion, a set screw mounted in said fitting and extending radially of said depressed portion adapted to hold said nipple engaged with the converging walls of said channel, whereby said nipple may be firmly connected with said pivotal member, an adjustable member carried by the other of said members adapted to engage the other element of said release mechanism, spaced fixed contacts, and a movable spring contact carried by one of said members intermediate said means and said adjustable member, and the axis of movement of said pivotal member, and a striker member carried by the other of said members and engageable with said spring contact, whereby the timing of the engagement of said contacts and the actuation of said release mechanism, may be varied without variation of the relative movement of said members, and an electrical circuit including said bulb and said contacts.

7. A flashlight apparatus embodying therein the combination with a camera having a shutter and a mechanical release mechanism therefor having immovable and movable elements, of a support for a flash bulb, a control device embodying therein two members pivotally connected adjacent one end thereof, one of said pivotal members having the sides and the end thereof adjacent the pivotal connection closed, and the front thereof provided with a slot therethrough, means adjacent the free end of one of said members, whereby one of the elements of said release mechanism may be connected therewith, an adjustable member carried by the other of said members adapted to engage the other element of said release mechanism, spaced fixed contacts, and a movable spring contact carried by one of said members intermediate said means and said adjustable member, and the axis of movement of said pivotal member, a striker member carried by the other of said members and engageable with said spring contact whereby the timing of the engagement of said contacts and the actuation of said release mechanism may be varied without variation of the relative movement of said members, and a barrier plate between said adjustable member and said electrical contacts, and an electrical circuit including said bulb and said contacts.

8. A flashlight apparatus embodying therein the combination with a camera having a shutter and a mechanical release mechanism therefor having immovable and movable elements, of a support for a flash bulb, a control device embodying therein two members pivotally connected adjacent one end thereof, means adjacent the free end of one of said members, whereby one of the elements of said release mechanism may be connected therewith, an adjustable mem-

ber carried by the other of said members adapted to engage the other element of said release mechanism, a movable spring contact carried by one of said members intermediate said means and said adjustable member, and the axis of movement of said pivotal member, spaced fixed contact pins carried by and insulated from the same pivotal member as said movable spring contact, each having one end in operative relation to said spring contact, and the other end exposed outwardly of said member so as to be engageable with a contact plug, and a striker member carried by the other of said members and engageable with said spring contact, whereby the timing of the engagement of said contacts and the actuation of said release mechanism, may be varied without variation of the relative movement of said members, and an electrical circuit including said bulb and said contacts.

9. A flashlight apparatus embodying therein the combination with a camera having a shutter and a mechanical release mechanism therefor having immovable and movable elements, of a support for a flash bulb, a control device embodying therein two members pivotally connected adjacent one end thereof, one of said pivotal members having the sides and the end thereof adjacent the pivotal connection closed, and the front thereof provided with a slot therethrough, a stop pin extending from side wall to side wall thereof, and the other of said pivotal members having side flanges provided with arcuate openings co-operating with said stop pin, a spring carried by one of said members and acting upon the other to normally separate said members, means adjacent the free end of one of said members, whereby one of the elements of said release mechanism may be connected therewith, an adjustable member carried by the other of said members adapted to engage the other element of said release mechanism, spaced fixed contacts, and a movable spring contact carried by one of said members intermediate said means and said adjustable member, and the axis of movement of said pivotal member, a striker member carried by the other of said members and engageable with said spring contact, whereby the timing of the engagement of said contacts and the actuation of said release mechanism, may be varied without variation of the relative movement of said members, and a barrier plate between said adjustable member and said electrical contacts, and an electrical circuit including said bulb and said contacts.

10. In a flashlight apparatus, a bulb support adapted to receive a dry cell battery, means whereby said support may be detachably connected with a camera comprising a fitting having an opening extending therethrough, an attaching screw rotatably mounted in the opening in said fitting, and having an elongated channel about and intermediate the ends thereof, a latch pin carried by said fitting and entering said channel, and a spring acting upon said latch pin, whereby said screw may be quickly withdrawn from said opening and replaced therein.

11. A flashlight apparatus embodying therein the combination with a camera having a shutter and a mechanical release mechanism therefor having immovable and movable elements, of a support for a flash bulb, a control device embodying therein two members pivotally connected adjacent one end thereof, means adjacent the free end of one of said members, whereby one of the elements of said release mechanism

of the elements of said release mechanism may be connected therewith, an adjustable member carried by the other of said members adapted to engage the other element of said release mechanism, and co-operating fixed and movable electrical contacts intermediate said means and said adjustable member, and the axis of movement of said pivotal members, whereby the

timing of the engagement of said contacts and the actuation of said release mechanism, may be varied without variation of the relative movement of said members, means whereby said support may be detachably connected with a camera, and an electrical circuit including said bulb and said contacts. 5
